C. M. ALEXANDER.
BRIDLE ATTACHMENT.

No. 34,343.

Patented Feb. 11, 1862.

Witnesses;
I am
M. Hines

Inventor;

UNITED STATES PATENT OFFICE.

C. M. ALEXANDER, OF WASHINGTON, DISTRICT OF COLUMBIA.

IMPROVEMENT IN BRIDLE-BIT ATTACHMENTS.

Specification forming part of Letters Patent No. 34,343, dated February 11, 1862.

To all whom it may concern:

Be it known that I, C. M. ALEXANDER, of Washington, in the District of Columbia, have invented certain new and useful Improvements in Bridle-Bit Attachments; and I do hereby declare that the following is a full, clear, and exact description of the same, reference being had to the accompanying drawing, and to the letters of reference marked thereon.

In the annexed drawing, making part of this specification, A represents one of the shanks or side pieces of the bit, to which the headstall and reins are attached. B is the ring in said shank for the headstall, and C and D are the rings for the reins. To the ring C, I attach a spring E, which is provided with a ring at its other end. F represents a strap, which passes from the ring D to the ring G on the end of the spring.

The bridle-rein in this case is attached to the ring G, and is marked H.

It will be readily seen that when an easy pressure is applied to the rein H the spring will act upon the bit direct; but as soon as a heavy pressure is applied the spring yields and the strap F causes the curb to act on the jaw of the horse.

The strap F may be made longer or shorter, thus putting on the curb sooner or later, or by more or less pressure. When the strap has more slack, of course there will be greater direct pressure on the bit, and it will take a harder pull on the reins to make the curb act.

Some horses may require the strap F to be

made short or direct from ring D to ring G, so that the curb may be let on gently the moment the rider begins to draw the reins.

The spring here used is of peculiar construction. I use a coiled-wire spring and run two wires through it from each end, such as are seen in Figure 1. The wires L have a loop, as seen, at one end, while they bend around at their other ends to embrace and catch upon the spring, as shown. When rings are inserted in the looped ends of the rods and these rings are drawn in opposite directions, the spring is contracted. When pressure is removed from the rings, the spring assumes its normal position. This form of spring attachment is the simplest and most effective of any used for contracting a spring, said attachment not being liable to objections on account of expensiveness in construction or inefficiency under the various circumstances to which it is necessarily exposed when used upon the bridle.

I do not claim the use of springs applied to bridle bits and reins of the general construction herein described; but

I do claim—

The arrangement of the looped wires L L, passing through the springs, when used in combination with the shank A, strap F, and bridle-rein H, as and for the purpose herein specified.

C. M. ALEXANDER.
